DESIGN FOR A RETINOSCOPE OR THE LIKE

William F. Peck, Snyder, Albin A. Gradisar,
Buffalo, and John T. Armbruster, Niagara Falls,
N. Y.

Application September 10, 1941, Serial No. 103,273

Term of patent 14 years

To all whom it may concern:

Be it known that we, (1) William F. Peck, (2) Albin A. Gradisar, and (3) John T. Armbruster, citizens of the United States, residing at (1) Snyder, (2) Buffalo, and (3) Niagara Falls, in the counties of (1) and (2) Erie and (3) Niagara and State of New York, have invented a new, original and ornamental Design for Retinoscope or the Like, of which the following is a specification, reference being made to the accompanying drawing, forming a part thereof.

Fig. I is a front elevational view of a retinoscope or the like embodying our new design; and

Fig. II is a side elevational view of the retinoscope or the like shown in Fig. I.

The characteristic features of the design reside in the portion shown in full lines in the drawing.

What is claimed is:

The ornamental design for a retinoscope or the like, substantially as shown and described.

WILLIAM F. PECK.
ALBIN A. GRADISAR.
JOHN T. ARMBRUSTER.
